MALLEABLE SHEET METAL FASTENER

Theodore Pasternak, Detroit, Mich., assignor to
Robert L. Brown, Ferndale, Mich.

Application October 14, 1953, Serial No. 385,965

1 Claim. (Cl. 85—38)

This invention relates to a malleable sheet metal fastener and more particularly to improvements in a fastener disclosed in United States Patent 2,618,193 issued November 18, 1952, to Roy E. Peckham, for securing panels together or a molding to a panel.

In that patent the fastener has a central bendable section with oppositely disposed engaging portions at opposite sides of the bendable section whereby each pair of engaging portions are brought into holding engagement with the panel by bending one pair of engaging portions toward each other, the central portion being forced into the panel opening.

It is an object of the present invention to provide inwardly turned flanges on a pair of the engaging portions which engage the central portion and are forced outwardly by the action of the central portion entering the opening in the panel when the fastener is applied.

A further object of the invention is to provide engaging portions on the pair of outwardly bent holding flanges which engage the central portion when the fastener is applied by deformation, so that the outwardly bent holding flanges are held in their bent position by the central portion.

Other objects and advantages of the invention will be more apparent from the following description taken in connection with the accompanying drawings in which:

Fig. 1 is a cross sectional view through a pair of panels showing the fastener in side elevation and before it is deformed to its retaining position;

Fig. 2 is a view corresponding to Fig. 1 showing the fastener bent to its retaining position;

Fig. 3 is a top plan view of Fig. 2; and

Fig. 4 is a perspective view of the fastener before it is deformed.

Referring to the drawings, the fastener comprises a sheet metal stamping formed from malleable metal which may be permanently deformed as distinguished from a spring steel metal which, when bent, will return to its normal position.

The fastener is formed from flat sheet material, cut to the desired shape, and bent in suitable dies to its finished shape and form. When finished there is provided a central body portion 10 and diverging arms 12 at substantially right angles to each other. The outer ends of the arms 12 are reversely bent upon the outer surface of the arms 12 to form arms 14 extending in converging relation toward the center of the body 10. The arms 14 reinforce the arms 12 and terminate short of the apex 16 to permit bending of the central portion at 16.

The outer free ends of the arms 14 are bent in spaced parallel relation extending away from the arms 12 and 14 forming projections 18 adapted for insertion in the openings O of the parts to be joined. The projections 18 are provided with inwardly turned flanges 20 therebetween which engage the apex 16 of the central body portion 10.

The arms 12 and 14 project laterally beyond the side edges of the central portion 16, forming shoulders 22 for contact with the under side of the panel with which the fastener is to be used. The laterally extending shoulders further increase the rigidity of the arms 12 and 14 and localize bending to the single thickness portion of the fastener at its central portion 16. If desired the

2

shoulders 22 may be confined to either the inner arms 12 or the outer arms 14.

The fastener is formed to the shape shown in Fig. 1 and is adapted to be inserted through openings O in overlapping panels P. The fastener is inserted from the underside of the panels and the shoulders 22 limit the position of the fastener by their engagement with the under surface of the panel. A suitable tool, such as a pair of pliers, is used to pinch the two divergent arms, formed by the arms 12 and 14, toward each other. This action causes a bending of the weakened central section 16 and the projections, fulcrumed on the surfaces of the bent central section, are bent away from each other in divergent relation into tight contact with the inner wall 15 of the openings in the panels, as illustrated in Fig. 2. Since the projections 18 are divergent the outer surfaces contact the outer edge of the opening and urge the upper panel toward the lower panel, the latter being held by the shoulders 22.

When the fastener is assembled, the bending together of the divergent arms causes the outer bending of the projections 18 which grip on the inner edge of the opening in the panel, and the weakened portion 16 is forced upwardly into the opening holding the arms in tight engagement with the side walls of the opening.

The edges of the tapered surface of the shoulders 22 bite into the edges of the opening in the under panel and prevent turning of the fastener relative to the panels. When the panels are comparatively thin, the tapered surface will deform the edge of the opening in the upper panel to cause the surface to engage the edge of the opening in the lower panel.

The central body portion 16 engages the ends of the inwardly turned flanges 20 and the upward movement of the portion 16 into the openings forces the flanges outwardly to thereby further assist in bending the flanges 18 over the edge of the opening in the upper panel and at the same time locks the flanges 18 against returning to their original position.

It will be understood that the invention is not limited to the specific form of locking means herein shown as many variations may be made, and I do not wish to limit the scope of the invention other than by the terms of the appended claim.

I claim:

A malleable fastener for insertion into a hole through a panel, said fastener consisting of a single strip of sheet metal bent along a transverse line midway of an intermediate portion and having its end portions folded back to engage along the outer surfaces of the intermediate portion to provide two divergent arms of double thickness and a pair of normally parallel arms extending beyond said intermediate portion for entering the hole through the panel, the outer portion of the length of said divergent arms having a width greater than the size of the panel opening, the intermediate portion, the end portions adjacent said intermediate portion and said arms having a lesser width to enter the hole through the panel, and forming a Y, each portion of which is of double thickness and of a length slightly greater than the thickness of said panel, the outer ends of said parallel arms being reversely bent toward each other and terminating in contact with the bend of said intermediate portion.
